ELECTRIC VACUUM CLEANER

Julian R. Haynes, Hinsdale, Ill., assignor to Sunbeam
Corporation, Chicago, Ill.

Filed July 12, 1971, Ser. No. 161,370

Term of patent 14 years

Int. Cl. D15—05

U.S. Cl. D49—14.3

Fig. 1.

Fig. 2.

FIG. 1 is a perspective view of an electric vacuum cleaner embodying my new design;

FIG. 2 is a side elevational view thereof showing the side opposite that shown in FIG. 1;

FIG. 3 is a top plan view thereof;

FIG. 4 is a front elevational view thereof; and

FIG. 5 is a rear elevational view.

I claim:

The ornamental design for an electric vacuum cleaner, as shown.
